CLAIM

The ornamental design for an adjustable beverage can storage organizer rack, as shown and described.

DESCRIPTION

FIG. 1 is a top perspective view of an adjustable beverage can storage organizer rack, showing my new design; FIG. 2 is a bottom perspective view thereof; FIG. 3 is a front elevation view thereof, the rear elevations view being a mirror image of FIG. 3; FIG. 4 is a left side elevation view thereof; FIG. 5 is a right side elevation view thereof; FIG. 6 is a top plan view thereof; FIG. 7 is a bottom plan view thereof; FIG. 8 is a partial enlarged view of FIG. 1; FIG. 9 is a partial enlarged view of FIG. 1; and, FIG. 10 is a partial enlarged view of FIG. 2. The broken lines in the figures demarcate enlarged areas and form no part of the claimed design.

1 Claim, 8 Drawing Sheets
